(57) **CLAIM**

The ornamental design for a weight training handle, as shown and described.

DESCRIPTION

FIG. 1 is an upper perspective view of a weight training handle showing my new design;

FIG. 2 is a side view thereof;

FIG. 3 is an opposite side view thereof;

FIG. 4 is a front view thereof;

FIG. 5 is a rear view thereof;

FIG. 6 is a top plan view thereof;

FIG. 7 is a bottom plan view thereof;

FIG. 8 is a lower perspective view thereof;

FIG. 9 is a perspective view illustrating the weight training handle affixed to a weight training machine, wherein the weight training handle is in a first position;

FIG. 10 is a side view illustrating the weight training handle affixed to a weight training machine, wherein the weight training handle is in a second position; and,

FIG. 11 is a perspective view illustrating the weight training handle affixed to a weight training machine, wherein the weight training handle is in a third position.

The broken lines in FIGS. 7 and 8 illustrate portions of the weight training handle that form no part of the claimed design. The broken lines in FIGS. 9-11 are directed to environment and are for illustrative purposes only; the broken lines form no part of the claimed design.

1 Claim, 11 Drawing Sheets
